UNITED STATES PATENT OFFICE.

GORDON FOX, OF CHICAGO, ILLINOIS, ASSIGNOR TO FREYN ENGINEERING COMPANY,
OF CHICAGO, ILLINOIS, A CORPORATION OF MAINE.

ROLL-HEATING MEANS.

Application filed June 4, 1923. Serial No. 643,198.

The present invention relates to roll heating means.

The finishing rolls in a sheet mill are commonly operated at high temperatures in order that the thin gauge metal being rolled may not be unduly cool. In starting operations it is necessary to bring up the temperature of the rolls, this raising in temperature being accomplished in some instances by passing heated sheet forming bars between the rolls. Steam, hot air, gas flame and other means have been employed for heating said rolls. Another common method is to apply heating elements in metallic contact with the periphery of the rolls, the heat being transferred to the rolls by conduction. The last mentioned method requires that the rolls be stationary during the heating operation. Though a sheet mill has been referred to by way of example, it will be clear that the invention is of broader application, being applicable to the heating of rolls in many arts.

An object of the present invention is to provide means for efficiently heating the rolls while said rolls are in rotation.

A further object is to provide means for heating the rolls of rolling mills by transmitting heat thereto by radiation and convection from a heating device located in close proximity to the periphery of the rolls but not in actual contact therewith.

A further object is to provide efficient means for electrically heating rolling mill rolls.

Further objects will appear as the description proceeds.

The one figure of the drawing represents, diagrammatically, one embodiment of the present invention.

The numeral 1 indicates a frame, which provides bearings for a pair of rolls 2-2. The frame 1 may be slidably mounted upon the tracks 3-3 for the purpose of permitting longitudinal movement of the frame 1 and the rolls 2-2. Each of the rolls has operatively associated therewith a heating device 4. The devices 4-4 may be electric heaters and each will preferably conform to the contour of its corresponding roller throughout a considerable proportion of the periphery of said roller and throughout a considerable proportion of the length of said roller. Said heating devices 4-4 will be held in spaced relation with the rolls 2-2,

though located in close proximity to said rolls. Any preferred holding means, as for instance the members 5-5, (which, it will be noted, are adjustable,) may be provided for holding the heaters 4-4 in their proper positions. It will be noted that the members 5-5 are attached to frame members 5^a-5^a, which are shown as being shaped in substantial conformity to the roll surfaces. Said frame members carry the heating elements 5^b-5^b by means of the heat confining cover 5^c. Each of the heaters 4-4 will be provided with electrical connectors 6-6. If preferred, the electrical circuits of the two heaters may be independent of one another, whereby the heating action of each heating device may be controlled independently of the other.

It will be clear that the heating devices 4-4 may be heated in other ways than by means of an electric current, though electric current is at present preferred. By reason of the present invention, the rolls 2-2 may be efficiently heated, either before the rolls are put in operation or while said rolls are rotating. Inasmuch as the heaters closely encircle considerable portions of the rolls, very little of the heat from said heating devices is lost, it being a simple matter to direct the heat rays inwardly to the rolls.

Though a preferred embodiment of the present invention has been illustrated, it will be clear that many modifications may be made without departing from the invention. It is intended in this patent to cover all such modifications that fall within the scope of the invention as defined by the appended claims.

What is claimed is:

1. In a sheet mill, a rotating roll, an electrical heating device conforming to the periphery of said roll throughout a substantial portion of said periphery, and means for holding said heating device in proximity to said roll but spaced therefrom, said heating device including electric heating elements and a heat confining cover for confining heat to said rolls.

2. In a sheet mill, a pair of rolls having their axes parallel, an electrical heating device operatively associated with one of said rolls and conforming to the periphery of said one roll throughout a substantial portion of said periphery, and means for hold-

ing said heating device in proximity to said roll but spaced therefrom, said heating device being disposed out of obstructing relationship with said rolls, said heating device including electric heating elements and a heat confining cover for confining heat to said rolls.

3. A heater of the character described, comprising a pair of complementary heater sections for mounting in jacketing relation to a set of rolls, and means for supporting said sections in such relation, each section comprising frame members shaped in substantial conformity to the roll surfaces to be embraced thereby, a plurality of electrical heating elements carried by said members

in position for lying adjacent to, but out of contact with, embraced rolls, and a heat confining cover supported by said members.

4. In combination, a pair of rolls, means for rotatably supporting said rolls, a heater arranged in circumferential relationship with one of said rolls, but spaced therefrom, said heater being disposed out of obstructing relationship with the pass between said rolls, and means for adjustably carrying said heater whereby the spaced relationship between said heater and its cooperating roll may be controlled.

Signed at Chicago, Illinois, this 31 day of May, 1923.

GORDON FOX.
